UNITED STATES PATENT OFFICE.

LEON T. MART, OF YOUNGSTOWN, AND GEORGE M. STAINS, OF CLEVELAND, OHIO.

VALVE-REGULATOR.

1,160,926.

Specification of Letters Patent. Patented Nov. 16, 1915.

Application filed December 13, 1913. Serial No. 806,552.

To all whom it may concern:

Be it known that we, LEON T. MART and GEORGE M. STAINS, citizens of the United States, residing at Youngstown and Cleveland, respectively, in the counties of Mahoning and Cuyahoga, respectively, and State of Ohio, have invented certain new and useful Improvements in Valve-Regulators; and we do hereby declare the following to be a full, clear, and exact description of the invention, such as will enable others skilled in the art to which it appertains to make and use the same.

This invention comprehends improvements in valve regulators and relates more particularly to a regulator for feed water valves for controlling the flow of water to a steam boiler, feed water heater or other reservoirs of analogous uses.

The primary object of the invention is to provide a feed water valve regulator which will be exceedingly sensitive to changes in water level so that a constant flow past the feed valve may be maintained; which operates without a waste of steam or water; which is unaffected by temperature and pressure changes; and which is of extremely simple and practical construction, having no needle valve, diaphragm, expansion elements and the like.

Another and more specific object of the invention is to provide a regulator of this type having a float which operates a slide valve, the latter serving to release the pressure from one side or the other of a piston or plunger which is operatively connected to the feed water valve.

As a further object, the invention contemplates the provision of a valve regulator which shall be a general improvement over devices of a similar nature now in use.

With these and other objects in view as will become more apparent as the description proceeds, the invention consists in certain novel features of construction, combination and arrangement of parts as will be hereinafter more fully described and claimed.

For a complete understanding of our invention, reference is to be had to the following description and accompanying drawings, in which—

Figure 1 is a vertical sectional view through our improved valve regulator, parts thereof being shown in elevation, Fig. 2 is fragmentary detail sectional view partly in

elevation, showing the float, slide valve casing, slide valve and coöperating parts, and Fig. 3 is a view showing in elevation a section of the feed water pipe, feed valve and valve lever.

Generally considered, the invention comprises a float chamber, a plunger or piston cylinder, a piston or plunger operable within said cylinder, pipes connected to the piston and extending into the float chamber, valve mechanism for controlling the flow of water from the cylinder to the float chamber and a float for operating the valve.

Taking up the parts in the order named, 70 5 designates, as an entirety, a cylindrical casing forming the float chamber 6 and comprising a body 7, a top wall 8 and a head 9 which closes the lower open end of the body. The body 7 and wall 8 are preferably formed 75 by a single casting and the body 7 is formed adjacent its upper and lower ends with the ports or openings 10 and 11 respectively. A pipe 12 is threaded into the opening 10 and is adapted to connect with a boiler or other 80 receptacle above the water line, and a pipe 13 is threaded into the opening 11 and is adapted to connect with the boiler or receptacle below the water line so that the water level within the float chamber corresponds to 85 the level within the boiler. The head 9 is preferably connected to the casing 5 by the cap screws 14.

Passing now to the piston or plunger cylinder 15, we see that it consists of a body 16 90 and heads 17 and 18. The head 17 is integrally connected to the head 9 by the arms 19 and has its inner or lower face centrally recessed, as indicated by the numeral 20 and threaded to receive the upper threaded terminal of the body 16. The head 18, which closes the lower end of the body 16, is formed with an internally threaded peripheral flange 21 which engages the threaded exterior of the body. Each of the heads 17 100 and 18 is formed with an angular port or bore 22 which opens upon the periphery of the head and upon the inner face thereof within the body 16. Pipes 23 and 24 connect the bores 22 with the feed water pipe 105 25 in advance of the feed water valve 26.

Taking up as next in order the plunger or piston 27, which operates within the cylinder 15, we see that it is formed with a central longitudinal bore 28, the upper end of which 110 opens upon a chamber or recess 29 of a greater diameter than the bore. The piston

is preferably cast integrally with a stem or rod 30 which extends through the head 18 and which is connected to the valve operating lever 31. Ports 30' are formed in the piston rod 30 adjacent the piston 27 and establish communication with the interior of the cylinder 15 and the bore 28.

A pipe 32 is threaded at its lower end into the recess 29 and extends upwardly through the heads 17 and 9 into the float chamber 6. This pipe is formed adjacent its lower end with a port 33 to establish communication between the interior of the cylinder 15 and the interior of the pipe 32. A second pipe 34 is threaded into the upper end of the bore 28 and extends through the pipe 32 in spaced relation to the interior thereof.

The means provided for controlling the flow of water from the cylinder 15 through the pipes 32 and 34 into the float chamber 6, includes a valve casing 35 formed in its lower end with a chamber 36 into which the upper terminal of the pipe 32 is threaded, as clearly shown in Fig. 2. The pipe 34 abuts the top of the recess 36, and is aligned with a longitudinal bore 37 extending through the casing 35 and communicating at its upper end with a transverse bore or passage 38. The casing is also formed with a longitudinal bore 39 which communicates at its upper end with the transverse bore 38 and at its lower end with the chamber 36 between the pipes 32 and 34. A slide valve 40 operates transversely of the casing 35 and is formed with a passage 41 which registers with the bores 37 and 39.

A saucer shaped shield 41' is formed integrally with the valve casing 35 and besides serving to prevent an undue agitation of the water within the float chamber 6, provides a support 42 for the pivoted float arm 43. This arm is pivoted at one end to the support 42 and has attached to its other end a float 44 which is positioned directly over the shield 41. A rod 45 is pivotally connected at its upper end to the arm 43, extends downwardly through an opening 46 formed in the shield and is connected at its lower end to one arm of a bell crank lever 47. This lever is pivoted to a laterally projecting stem 48 carried by the casing 35 and is connected to the slide valve 40.

Having described the construction of the feed water valve regulator, it now remains to explain the operation thereof and in order to simplify this portion of the description, we will assume that the device is used to regulate the water level within a boiler. The casing 5 is mounted so as to extend above and below the water level in the boiler and as before stated the pipes 12 and 13 are connected to the boiler above and below the water level respectively. The piston rod 30 is connected to the lever 31 of the feed valve

26 and the pipes 23 and 24 are connected to a pipe 49 which is communicant with the feed water pipe 25. With the water at the desired level within the boiler, the plunger rod 30 is connected to the lever 31 so that when the float 44 is properly supported by the water in the float chamber 6, the valve 26 will be set so as to allow the desired amount of water to feed into the boiler, to compensate for the normal loss of water by using the steam generated. The pressure of the feed water is maintained at a greater degree than the boiler pressure, and the ports of the valve casing 35 are designed to allow water to flow more rapidly into the float chamber 6 than it enters the cylinder 15 through the bores or ports 22. With these observations in mind, it will be seen that a rise of water level within the boiler will lift the float 44, causing the passage 41 of the slide valve to register with the passage 39 in the casing 35, at which time water will flow from the upper end of the cylinder 15, through the pipe 32 into the float chamber 6, and since water may exhaust from the cylinder 15 more rapidly than it may flow thereinto, it is evident that the pressure upon the top of the piston 27 will be reduced. The piston will then raise the float to the new level and reduce the volume of water flowing through the valve 26. Should the water level continue to rise, the plunger 27 will again move upwardly until the valve 26 is entirely closed.

When the water level within the boiler drops, the float drops and actuates the slide valve 40 to bring its port 41 into registration with the passage 37 at which time water will exhaust or flow from the lower side of the piston 27 into the float chamber through the pipe 34 and reduce the pressure upon the underside of the piston. The pressure being thus reduced, the piston will move downwardly because of the pressure exerted by the feed water upon its upper end and the valve will be opened, or if already opened will be further opened to allow a more rapid flow of water into the boiler. Each movement of the piston 27 readjusts the position of the float with respect to the water level in the float chamber so that the float remains normally supported entirely by the water within the float chamber, at which time the valve 40 is closed.

From the foregoing description taken in connection with the accompanying drawings, it will be seen that we have provided a very simple, practical and substantial feed water valve regulator, which is very sensitive to changes of water level; which is devoid of intricate mechanism; which is unaffected by temperature or pressure changes; and which operates without a waste of steam or water.

While we have shown and described the

preferred embodiment of our invention, it will be understood that minor changes in construction, combination and arrangement of parts may be made without departing 5 from the scope and spirit of the invention as claimed.

Having thus described our invention, we claim:—

1. A feed water regulator including a 10 float chamber, pipes connecting the float chamber with a boiler above and below the water line, a cylinder supported below the float chamber, a piston slideable in the cylinder, a stem carried by the piston and operatively connected to the feed water valve of the boiler, pipes connecting the cylinder with the feed water supply at a point beyond the valve, a pipe secured to the upper end of the piston and communicating with the upper 15 part of the cylinder, said pipe extending into the float chamber, a second pipe located within the first mentioned pipe and spaced therefrom the second pipe communicating with the lower portion of the cylinder and extending into the float chamber, means controlling the flow of water through the pipes, and a float controlling the operation of the water flow controlling means.

2. A feed water regulator including a 20 float chamber in communication with a boiler above and below the water line, a cylinder supported below the float chamber, a piston slideable in the cylinder, a feed water valve operatively connected to the piston and arranged to be controlled thereby, pipes connecting the cylinder with the feed water supply at a point beyond the feed water valve, a pipe connected to the upper end of the cylinder and communicating with the upper 25 portion of the cylinder, said pipe extending into the float chamber, a second pipe

located within the first mentioned pipe and spaced therefrom communicating with the lower portion of the cylinder, the second pipe extending into the float chamber, a 45 valve at the upper end of the pipe, said valve controlling the flow of water through the pipe, and a float supported at the upper end of the valve to control the operation thereof.

3. A feed water regulator including a 50 float chamber in communication with a boiler above and below the water line, a cylinder located below the float chamber, a piston operable within the cylinder, the piston being operatively connected with the feed water valve, pipes connecting the cylinder with the feed water supply at a point beyond the feed water valve, a pipe connected to the upper end of the piston and 55 extending into the float chamber, a second pipe within the first mentioned pipe, the first and second mentioned pipes communicating respectively with the upper and lower portion of the cylinder, a valve casing secured to the upper end of the pipe, said casing being provided with ports communicating with the respective pipes, a valve slideable in the casing, and arranged to close the ports, a shield carried by the valve casing, a float arm pivoted to the shield, a float carried by the float arm, and means connecting the float arm with the valve to control the operation thereof.

In testimony whereof we affix our signatures in presence of two witnesses.

LEON T. MART.
GEORGE M. STAINS.
